UNITED STATES PATENT OFFICE.

CLYDE D. PECK, OF CHICAGO, ILLINOIS.

DESIGN FOR A MEDAL OR BADGE.

No. 39,329.

Specification for Design.

Patented June 2, 1908.

Application filed March 30, 1908. Serial No. 424,291. Term of patent 7 years.

To all whom it may concern:

Be it known that I, CLYDE D. PECK, a citizen of the United States, residing at Chicago, in the county of Cook and State of Illinois, have invented a new, original, and ornamental Design for Medals or Badges, of which the following is a specification, reference being had to the accompanying drawing, forming part thereof

The drawing is a perspective view of a medal or badge embodying my new design.

I claim:

The ornamental design for a medal or badge as shown.

CLYDE D. PECK
